UNITED STATES PATENT OFFICE.

JOHN M. ALFORD, OF CHICAGO, ILLINOIS.

DISPLAY-CASE.

SPECIFICATION forming part of Letters Patent No. 764,028, dated July 5, 1904.

Application filed October 24, 1903. Serial No. 178,362. (No model.)

To all whom it may concern:

Be it known that I, JOHN M. ALFORD, a citizen of the United States, residing at Chicago, in the county of Cook and State of Illinois, have 5 invented new and useful Improvements in Display-Cases, of which the following is a specification.

My invention relates to new and useful improvements in display-cases for cans containing crackers, cakes, &c. Its object is to provide a simple and inexpensive device formed of sections any number of which are adapted to be quickly connected and which provides an inexpensive and attractive holder for cans 15 especially adapted for use in stores.

The invention consists in forming a case of a desired number of sections, each of which is preferably constructed of L-shaped corner-strips having intermediate connecting-strips 20 whereby a rectangular case is produced. The connecting-strips have apertures therein for the reception of bolts, whereby two or more sections may be fastened together to form a complete case.

25 The invention also consists in the further novel construction and combination of parts hereinafter more fully described and claimed, and illustrated in the accompanying drawings, showing the preferred form of my invention, 30 and in which—

Figure 1 is a perspective view of a case-section and showing in dotted lines a can in position therein. Fig. 2 is a section through the case formed of sections bolted together. 35 Fig. 3 is a perspective view of a modified form of case-section, and Fig. 4 is an elevation thereof and showing smaller case-sections secured thereto.

Referring to the figures by numerals of reference, 1 1 are L-shaped corner-strips, each of which has grooves 2 in the center portions of its edges, and these grooves are adapted to receive tongues 3, projecting from the ends of connecting-strips 4. The tongues may be 45 secured in the grooves in any suitable manner, as by means of glue, and the connecting-

strips are preferably provided with central apertures 5. The frame produced by the corner and connecting strips may be of any desired size and forms a case for a can 6, (shown 50 in dotted lines in Fig. 1,) and which is adapted to be slid into or from the case, as desired. The apertures 5 are countersunk, as shown at 7, to receive the heads of bolts 8, whereby two or more sections may be securely fastened together, as shown in Fig. 2.

If desired, each of the case-sections may be constructed with a multiplicity of openings, as shown in Fig. 3, in which the case-section is shown with four can-receiving portions. 60 This modified section is constructed of a central X-shaped strip 9 and L-shaped corner-strips 10. Interposed between the corner-strips are T-shaped strips 11, the tongues 12 of which are in alignment with the edges of 65 the central strip 9. Connecting-strips 13 are arranged between the L-shaped and T-shaped strips 10 and 11 and are provided with apertures 14, similar to the apertures 5, herein-before referred to. Connecting-strips 15 are 70 also interposed between the tongues 12 and the edges of the central strip 9 and serve to securely connect all of the strips of the case and to form a solid article. As shown in Fig. 4, one or more of the case-sections, such as 75 shown in Fig. 1, may be fastened to the section illustrated in Fig. 3, such connection being made by means of bolts 8, arranged within the apertures 5 and 14. It will also be understood, of course, that two or more of 80 the modified case-sections may be fastened together. When several sections, such as herein described, are secured together, an attractive case is formed in which cans can be readily inserted and securely held. The case 85 is very simple and inexpensive in construction and can be readily set up.

In the foregoing description I have shown the preferred form of my invention; but I do not limit myself thereto, as I am aware 90 that modifications may be made therein without departing from the spirit or sacrificing

any of the advantages thereof, and I therefore reserve the right to make such changes as fairly fall within the scope of my invention.

Having thus described the invention, what 5 is claimed as new is—

1. A case of the character described comprising L-shaped corner-strips, and apertured connecting - strips interposed between the edges thereof.
- 10 2. A case of the character described comprising L-shaped corner-strips having grooves in the edges thereof, connecting-strips intermediate the corner-strips and having apertures therein, and tongues to the connecting- strips adapted to be seated and secured within the grooves.
- 15 3. A case comprising a plurality of sections,

each section consisting of corner-strips, and apertured connecting - strips secured to the edges thereof, and means for securing the connecting-strips of the sections together. 20

4. A case of the character described comprising a central strip, corner-strips, longitudinally-extending strips interposed between the corner-strips, apertured connecting-strips 25 between the corner and intermediate longitudinally-extending strips, and connecting-strips between the central and intermediate strips.

In testimony whereof I affix my signature in presence of two witnesses.

JOHN M. ALFORD.
